[57] CLAIM

The ornamental design for a water fountain, as shown and described.

DESCRIPTION

FIG. 1 is a perspective view of a water fountain showing my new design on an enlarged scale; FIG. 2 is a side elevational view thereof; FIG. 3 is a top plan view thereof; FIG. 4 is a front elevational view thereof; FIG. 5 is a rear elevational view thereof; FIG. 6 is a bottom plan view thereof; and, FIG. 7 is an opposite side elevational view thereof. The bottom portion of the tee is shown broken away to indicate an indeterminate length.
